UNITED STATES PATENT OFFICE.

EDGAR G. MORIN, JR., OF SAN FRANCISCO, CALIFORNIA.

COMBINATION TOOL.

Application filed February 12, 1927. Serial No. 167,794.

This invention relates to combination tools, and more particularly to tools that are employed by workers in the building trades.

The primary object of this invention is to provide a hand tool that combines several tools in one and furnishes a useful article that may be used by carpenters, masons, plumbers, etc., with a consequent saving of time, labor and expense.

10 To produce such a tool, a combination of an adjustable miter square, a perpendicular and a horizontal level bubble, a rule and a sliding marker adjustable on a scale, is effected.

15 A particular advantage of this combination is the elimination of several separate tools, which are commonly larger and more cumbersome, thus permitting the artisan to carry in his pocket this small hand tool

20 which replaces several others.

Some of the numerous uses to which this tool may be applied are: to mark cutting lines on interior and exterior trim, baseboards, capping, casings, siding, corner boards and 25 all mill work; to get miter angle for any cut; to get plumb and bevel lines; and to scale small dimensions.

A further advantage lies in the arrangement and construction of parts which produce a tool capable of smooth precision in its 30 adjustments, facility in its manipulation, and one in which the appearance of sturdiness, quality and master workmanship are apparent.

35 The foregoing constitutes a recital of some of the advantages of my invention which is more fully explained by reference to the drawings, in which:

40 Figure 1 shows a side elevation of the tool in closed position;

Figure 2 shows a front elevation of the tool in partly open position;

45 Figure 3 shows a view of the operating plates and adjustable blades removed from the frame;

Figure 4 shows an enlarged sectional view on line 4—4 of Figure 5;

Figure 5 shows fragmentary front elevation with blades fully extended;

50 Figure 6 shows fixed slotted plate; and Figure 7 shows movable slotted plate.

Referring now in detail to the drawings, the tool is composed of two bifurcated frame members generally designated 1 and 2, two

adjustable blades generally designated 3 and 4, a fixed slotted plate generally designated 5, a movable slotted plate generally designated 6, and accessory screws and rivets with minor parts that will be described as their function becomes a part of the description. 55

A slot 7 is provided between 1 and 2 by cutting a portion from each leg. A lower bearing surface 8 is provided below the slot and the members 1 and 2 are held together by screws 9 and 10. An upper bearing surface 11 is provided by not cutting away that portion above the bifurcation on the members 1 and 2, which is best shown below level bubble 12, in Figure 2, and bounded by the dotted lines 13. A counter sunk screw 14 65 serves to hold the top portions together while a dowel pin 11' serves to align the parts when assembling. The above construction provides a frame with space between the two frame members 1 and 2 from the point 14 70 to the top, with the exception of the top bearing surface 11. 75

The frame member 2 is further recessed as at 15 to provide a slide way for the movable plate 6, but small portions 16 and 17 are left 80 at the outer edge to serve as guides.

Substantially in the center of this recess there is provided an elongated recess 18 in the member 2 which recess furnishes a slide-way and guide for block 20. 85

The frame member 1 is recessed as at 21 to take the fixed plate 5 which is held immovable by screws 22 and 23 to said member 1.

Said member 1 is slotted as at 25, which slot is provided with a peripheral shoulder 26. Through this slot extends a screw 27 fixedly attached to said block 20. A thumb nut 28 screws down onto a washer 29 which washer rests upon the aforementioned shoulder 26. 90

A small spacer block 30 is inserted between the plates 5 and 6 around the screw 14. It is not essential to the operation of the tool. 95

The blades 3 and 4 lie between the plates 5 and 6 as best shown in Figure 4, and are pivotally held to the sliding block 20 by pins 32 and 33. Each blade is also furnished with a pin 35, which pins extend out on each side and on one side engage the straight slots 36 cut in the stationary plate 5 while on the other side they engage curved slots 37 cut in plate 6. 100

In Figure 6, plate 5 which in the assembly is held immovable by screws 22 and 23 which are counter sunk and fit into holes 39 and 40,

is also provided with a slot 41, which slot coincides with slot 25 when assembled, while the hole 42 accommodates the screw 14. The lower part is cut away as at 43 to fit over the bubble 12.

In Figure 7, plate 6 which is the movable plate is provided with an opening 45 which is designed to take block 20. The opening 45 is made slightly longer than the block as shown at 46, Figure 4, but is a sliding fit as to width. The upward and downward play is necessary to prevent a binding taking place when the blades are moved in or out, since the vertical movement of the plate 6 is dependent upon the shape of the curved slot 37, and the travel of the block dependent on the straight slot and movement of pin 35. In actual practice the block 20 travels further than the plate 6. The slot 47 is provided to clear the screw 14 as the plate moves downward. The bottom part is shaped as at 48 to fit over the bubble 12.

In plates 1 and 2 a corresponding opening 49 is furnished to make the bubble 12 visible from either side.

Provided in one of the legs, or, if desirable, in each leg, is a plumb bubble 50 with an opening 51 and a second opening 52 provided at a right angle to each other to allow the bubble to be seen from either side of the leg or from the edge of the tool.

One of the legs of the member 1 and also of the member 2 is scored into inches and fractions, or in any other system desired, to serve as a small dimensional rule. A sliding member generally designated 55 is furnished, adapted to slide between the legs of the frame members 1 and 2 and utilizes the inner side of the slot 7 as a slideway. It is provided with an upstanding part 56 which may be used by the thumb to push it along, also with flat runners 57 and 58 which travel the slots 7.

A portion of the metal is cut away as at 60 and 61 to lighten the tool for carrying purposes.

The movement which takes place when the blades are changed from one angle to another is made up of three components: a horizontal movement, a vertical movement, and a curvilinear movement. By the above combination a result is obtained that produces a

rotating movement with neither a pivot nor a fixed point as a center.

As plate 6 is forced into the tool the pins 35 which engage both slots 36 and 37 move outward along slot 36, due to the pressure exerted by slot 37 in its downward movement. But said pins are fixed to the blades 3 and 4. Therefore the blades move outwardly, but since the blades are rotatably pivoted to the block 20 it follows that the block 20 moves downwardly, thus rotating the arms 3 and 4 on the pins 35 as the pins 35 continue to move back in the slots 36. The movement is completed, as shown in Figure 5, when the pins 35 have run into the ends of slots 37 which brings the arms 3 and 4 into a horizontal position.

At any point in this operation the movement may be stopped and the thumb nut 28, which, before commencing the movement, had been loosened, may be tightened, thus setting the arms fixedly in any angle desired.

When the blades 3 and 4 are sheathed in the slots 7, the tool presents a smooth surface, which makes it difficult to get at the blades to start them outward. To overcome this a point 65 is provided on the movable plate 6. This extends at all times out of the slot at the top of the tool. By placing the point on any sufficiently hard surface the plate 6 is pushed inward and the blades come out, providing a simple efficient means of operation.

The foregoing description and drawings show only one embodiment of my idea and since it is possible to refine and improve it without departing from the scope of the drawings, specifications or appended claim, I reserve this right of modification.

I claim:

In a combination tool, a frame, a member having slots therein and being fixedly secured to said frame, an adjustable member slidable in said frame and having a slideway formed therein, a block disposed in said slideway, adjustable blades having their ends pivoted on said block, said adjustable member having arcuate slots formed therein, and pins secured to said blades and extending into said slots in both the fixedly secured and the adjustable members.

EDGAR G. MORIN, JR.
